UNITED STATES PATENT OFFICE.

JOHN O. MORRIS, OF WASHINGTON, DISTRICT OF COLUMBIA.

TOBACCO-LEAF STEMMING, STRAIGHTENING, AND BOOKING MACHINE.

1,381,489.

Specification of Letters Patent. Patented June 14, 1921.

Application filed March 30, 1921. Serial No. 456,841.

To all whom it may concern:

Be it known that I, JOHN O. MORRIS, a citizen of the United States, residing at Washington, in the District of Columbia, 5 have invented certain new and useful Improvements in Tobacco-Leaf Stemming, Straightening, and Booking Machines, of which the following is a specification.

This invention relates to a tobacco stem-10 ming machine in combination with mechanism for straightening out the tobacco leaves from the bunched condition in which they are left immediately after stripping the leaf from the stem.

15 The invention furthermore provides a machine in which the length of stem taken from the leaf may be regulated, thus permitting the operator of the machine to regulate the length of the stem stripped from the leaf dependent on the kind of tobacco operated 20 upon and the use to which it is to be put after being stemmed.

25 In the past it has been the practice to stem tobacco leaves by carrying the said leaves on a movable belt to a position wherein the butt ends of the leaves are engaged by stripping and stem gripping means for the purpose of stripping the leaf from the stem as the latter is pulled through the strip-30 ping means.

35 In the present invention each individual leaf is straightened out and placed in proper position on an operator's platform and is fed by the operator directly to the stripping and stem gripping means, after which it is carried on into mechanism for straightening the leaf out.

40 In the accompanying drawings forming a part of this specification, and in which I 45 have illustrated a machine constructed in accordance with the principles of the present invention:

Figure 1 is a perspective view showing the complete machine.

45 Fig. 2 is an enlarged fragmentary view showing, in detail, the stripping and leaf straightening means.

Fig. 3 is a top plan view of the machine.

Fig. 4 is a side elevation of the machine 50 from the left hand side.

Fig. 5 is a fragmentary perspective of a modified form of stripping means.

Fig. 6 is a fragmentary side elevation of a modified form of stem gripping means.

55 Fig. 7 is an end elevation of the stem gripping means shown in Fig. 6.

Fig. 8 is a side elevation of the tampico member.

Fig. 9 is a sectional view on the line 9—9 of Fig. 8.

Referring to the drawings in detail:

The machine, as herein shown, comprises a base 1 upon which the parallel upright frame members 2—2' are mounted. The upright frame members 2—2' carry cross 65 pieces 3—3', respectively, supporting bearings 4 which journal the shaft 5 of a stripping drum 6, the construction of which will be hereinafter set forth. The frame members 2—2' are provided with lateral exten-70 sions 7—7' which receive and support an operator's feeding platform having the vertical gage 9 which is adjustable laterally of the said platform 8 by means of the studs 9' working in slots in the brackets 10. The 75 upper or working surface of the platform 8 is substantially tangent to the surface of the stripping drum 6.

The stripping drum is composed of two end members 11 and 12, the latter of which 80 is of wheel-like form and has a peripheral channel formed by the removable side flanges 108 between which is a circular series of brush-like members 14 secured in place by transverse wires 110 or any other suitable 85 means. These brush-like members may be of tampico fibers or other equally adaptable material.

Upright extensions 15 and 16 of the frame member 2' carry bearings 21 and 22 in which 90 are journaled stub shafts 23 and 24 having keyed thereto the chain sprockets 25 and 26, respectively, over which a stripping chain 17 travels. The chain 17 comprises a flexible base formed of two parallel side 95 strips connected by cross pins 18' which serve to form the sprocket engaging means and also fasten the stripping knives 19 between the said strips. Each knife 19 is provided with edge notches 20 for receiving the 100 butt end of a tobacco leaf stem and holding it against the brush-like members 14 during the stemming operation. The lower run of the chain 17 is substantially tangent to the periphery of the box-like members 14. In order 105 to take the slack out of the chain 17 and keep this lower run of the said chain in proper relation to the said brush-like members 14, the cross bar 27, which connects the upright extensions 15 and 16, is provided with a 110 bracket 28 journaling the double ended nut 29 having oppositely threaded ends. The

upper end thereof receives the threaded end 30 of a forked bracket 31 which carries the idler 32 over which the upper run of the chain 17 travels, while the lower end of the nut 29 receives an oppositely threaded end 33 from the end 30 and which carries a bearing shoe 34 of channel form, having rolls 35, beneath which the lower run of the chain 17 travels; therefore, by turning the nut 29 5 the slack in the chain 17 may be adjusted and any desired degree of pressure of the lower run of the chain on the brush-like members 14 may be obtained. Projecting from the extension 16 and overlying the drum 6 adjacent the lower run of the chain 17 is a leaf holding wire 36 beneath which the butt ends of the leaves of tobacco travel.

The two end members 11 and 12 of the stripping drum 6 are joined by slat-like 20 members 13 which form the body of the drum. Extending around the drum 6 and spaced from the brush-like members 14 at a distance approximately equal to the average length of tobacco leaf is a countersunk 25 annular peripheral channel member 13' having the side flanges 15' which journal rollers 16' in closely adjacent relation. Running around the drum 6, on the said rollers 16', is a belt 37 which also travels over an idler 30 pulley 38 carried on a shaft 39 at the side of the machine, said shaft being supported in bearings 40. The shaft 39 carries a pulley 41 which is driven by a belt 42 from a motor 43. At the opposite end said shaft 39 carries 35 a gear 44 meshing with an identical gear 45 carried on a stub shaft 46 and which, in turn, meshes with another identical gear 47 on a stub shaft 48; the last mentioned gear, namely 48, meshes with the gear 49 on a 40 shaft 24 thereby driving the sprocket 26 and chain 17.

The shaft 39 carries a sprocket 39' which is connected to a sprocket 5' on the shaft 5 by a chain 6' to drive the drum 6. The relation between the driving means for the belt 37 and the drum 6 is such that the belt 37 is driven faster than the drum 6, the reason for which will hereinafter appear.

On the outside of the machine and carried 50 by the spaced brackets 50-50 and 51-51 are the means for gripping and drawing the stem; such means consists of pulleys 52 and 53, the spindles of which carry grooved pulleys 54 and 56, respectively, over 55 which is trained the crossed belt 56, as shown, whereby driving the pulley 52 also drives the pulley 53. The remaining end of the shaft of pulley 52 is extended and carries a worm 57 which meshes with and 60 is driven from a worm wheel 58 on the shaft 23. At the adjacent ends of brackets 50-50 and 51-51 are journaled two small rolls 59 and 60, respectively, and which are so located that the opening therebetween is 65 wedge-shaped, as shown, with the smaller

end of the opening pointing away from the operator's platform 8. A stemming belt 61 is trained around pulley 52 and roll 59 and a similar belt 61' is trained around pulley 53 and roll 60, both belts moving to pull 70 the stem of a leaf away from the chain 17 as the stem enters the wedge opening by reason of the driving connections hereinbefore referred to.

A bracket 62 extends from the upright 75 15 of the frame member 2 and carries a forked end 63 which mounts an idler 64 directly over the belt 37 at a point immediately in back of where the stemming of each individual leaf occurs. Over this idler runs a leaf straightening belt 64, driven 80 from a pulley 66 on a shaft 67, which is just above the shaft 39; shaft 39 carries a gear 68 which meshes with a gear 69 on shaft 67 so that the leaf straightening belt 85 65 runs at the same speed as the belt 37 but both run faster than the drum 6.

Instead of using the tampico members 14 on the drum 6, the periphery of the said drum may comprise a series of radially disposed stripping knives, each of which is indicated by the numeral 70 and is provided with its working edge identically notched with respect to the coöperating knives of the flexible series of the belt 17. This construction, for some purposes, does equally 90 as well as the combination of knives and tampico members.

For stemming, the stem gripping means previously described may be replaced, if 100 desired, with a pair of rollers 71 and 72 having spindles 73 and 74 journaled in the bearings 75 and 76 of the brackets 77, these rollers being disposed with their axes substantially parallel and the surfaces of the 105 rolls slightly spaced apart. One of the rollers may be of metal as for instance roller 72 while the other, 71, may have a rubber gripping covering 77. The entrance side of the rollers is formed into a wedge shaped 110 opening 78 by tapering the respective rollers as indicated at 79 and 80. On the spindle 73 is a gear 81 meshing with a gear 82 on the spindle 74 so that driving one roller drives both; the spindle 74 carries a sprocket 115 83 which is driven from the machine in any suitable manner.

In the use of either type of stemming means hereinbefore described, a knife 84 may be fixedly in approximately the position indicated in Fig. 4 and will serve to 120 cut the stem of each leaf at any predetermined length depending on the speed of the stemming means and the rate at which the leaf travels through the machine.

In order to provide for booking the leaves, the stemmed product leaving the machine is delivered onto a belt A which is driven by a pulley 85 on a shaft 86 through the medium of the gear 89. The belt A 130

also runs over an idler 90 carried on an upright bracket 91. Parallel with the bracket 91 is another upright bracket 92 and between these brackets is mounted a shaft 93 which supports a tray 94 held in a substantially horizontal position by a spring 95. This tray is tiltable through the medium of a cam 96 on the end of the shaft of the roller 90 and which cam engages a lug 97 on the said tray 94. Beneath the tray 94 and running at right angles to the belt A is a belt B which runs over pulleys 98, one of which pulleys is a driving pulley for the pulley 99 of a booking belt 100 which is superposed on the belt B and is carried on pulleys 99 and 101, said drive being accomplished through the medium of a chain 102 or any other suitable means. The belt B may be driven from the idler 90 by means 20 of a pulley 103 carrying a belt 104 running over a pulley 105.

In making up the tampico members a spoked or solid disk may be used, the spoked type being indicated in Fig. 8 and consisting of a body 106 having a rim 107 provided with removable side flanges 108 held in place on the rim 107 by screws 109. The tampico is cut to proper length and looped and held in place by pins 110 so that the ends of the tampico lengths project substantially radially outward as shown. The pins 110, if desired, may be riveted over to hold them in place, or otherwise semi-permanently located.

35 The operator's platform 8 is attached to the members 7 through the medium of bolts 111 passing through slots 112 in members 113 carried by the said operator's platform 8 and thus rendering the same adjustable as 40 to vertical height; also, the platform is slotted as indicated at 114 for adjustment to and from the operating mechanism of the machine.

The operation of the machine is as follows:

An operator sitting on the right hand side of the machine at the platform 8 places the leaves as shown in Fig. 1 with the butt ends of the stems against the gage member 50 9. Power being applied to the machine by energizing the motor 43, the stripping drum 6 rotates in the direction indicated by the arrow in Fig. 1. This motor also drives the various other mechanisms of the machine and the operator then moves each individual leaf from the platform and into position to be gripped between the brush-like members 14 and the knives 19 of chain 17. Each leaf with its stem resting on the 55 60 tampico members 14 travels between the wire 36 and said tampico members and is engaged by one of the notches of one of the stripping knives 19 at which point the rapidly moving belts 61-61' grip the end 65 of the stem and draw it from the leaf. This

leaves the leaf in a bunched up condition with its butt end held beneath the wire 36 and its apex end, which is fairly straight, lying directly on the belt 37. The tendency of the wire 36 to hold the butt end of the 70 leaf while the drum moves causes the apex end of the leaf to engage between the leaf straightening belts 37 and 65 which are moving faster than the drum 6, and by reason of the holding of the one end of the leaf by 75 the wire 36, and the consequent sluing around of the other end by the difference in speed between the drum 6 and the two belts 37 and 65, the leaf is stretched out or straightened and is finally dropped down 80 onto the belt A.

The leaf is delivered by the belt A to the tray 94 which is tilted by the operation of the cam 96, thereby delivering the leaf in a transverse position onto the belt B. The 85 leaf then passes between the belt B and the belt 100 and is thereby booked and finally emerges from between the two belts into any suitable sort of a collector such as indicated at C.

90 While, in the foregoing, I have described a specific embodiment of the stemming machine, it is nevertheless to be understood that, in practice, I may resort to any modifications falling within the scope of the appended claims.

I claim:

1. In a tobacco stemming machine, co-operating stripping means, one of which comprises a drum constituting a leaf carrier successively positioning individual leaves in stripping position, and stem gripping means engaging and drawing each leaf stem as the leaves arrive at the stripping position.

100 2. In a tobacco stemming machine, co-operating stripping means, one of which comprises a rotating drum constituting a leaf carrier successively positioning individual leaves in stripping position, and stem gripping means engaging and drawing each leaf stem as the leaves arrive at the stripping position.

110 3. In a tobacco stemming machine, co-operating stripping means including continuously moving elements, one of which moves lineally and the other rotatively, for successively moving individual leaves to stripping position, and stem gripping means engaging and drawing each leaf stem as the leaves arrive at stripping position.

120 125 4. In a tobacco stemming machine, co-operating stripping means including continuously moving elements, one of which moves lineally and the other rotatively for successively moving individual leaves to stripping position, and stem gripping means engaging and drawing each leaf stem as the leaves arrive at stripping position.

5. In a tobacco stemming machine, co-

- operating stripping means, one of which comprises a flexible lineally moving member and the other a rotating drum constituting a leaf carrier successively positioning individual leaves in stripping position, and stem gripping means engaging and drawing each leaf stem as the leaves arrive at the stripping position.
6. In a tobacco stemming machine, co-operating stripping means, one of which comprises a lineally moving flexible member and the other a rotating drum constituting a leaf carrier successively positioning individual leaves in stripping position, and stem gripping means engaging and drawing each leaf stem as the leaves arrive at the stripping position.
7. In a tobacco stemming machine, co-operating stripping means, one of which comprises a lineally moving flexible knife member and the other a rotating drum constituting a leaf carrier successively positioning individual leaves in stripping position, and stem gripping means engaging and drawing each leaf stem as the leaves arrive at the stripping position.
8. In a tobacco stemming machine, co-operating stripping means including continuously moving elements, one of which moves lineally and the other of which comprises a rotatively moving carding member, the latter member also acting to successively move individual leaves to stripping position, and stem gripping means engaging and drawing each leaf stem as the leaves arrive at stripping position.
9. In a tobacco stemming machine, co-operating stripping means including continuously moving elements, one of which moves lineally and comprises a flexible series of knives, and the other of which comprises a rotatively moving carding member, the latter member also acting to successively move individual leaves to stripping position, and stem gripping means engaging and drawing each leaf stem as the leaves arrive at stripping position.
10. In a tobacco stemming machine, co-operating stripping means including continuously moving elements, one of which moves lineally and comprises a flexible series of knives, and the other of which comprises a rotating drum having a peripheral carding area, the said drum constituting a leaf carrier for successively moving individual leaves to stripping position, and stem gripping means engaging and drawing each leaf stem as the leaves arrive at stripping position.
11. In a tobacco stemming machine, co-operating stripping means including continuously moving elements, one of which moves lineally while the other rotates, the latter also constituting a leaf carrier for successively moving individual leaves to stripping position, and stem gripping means comprising adjacent belts engaging and drawing each leaf stem as the leaves arrive at the stripping position.
12. In a tobacco stemming machine, co-operating stripping means, one of which comprises a lineally moving flexible member, and the other a rotating drum constituting a leaf carrier, successively positioning individual leaves in stripping position, and stem gripping means comprising adjacent belts engaging and drawing each leaf stem as the leaves arrive at the stripping position.
13. In a tobacco stemming machine, co-operating stripping means, one of which comprises a lineally moving flexible knife member, and the other a rotating drum constituting a leaf carrier successively positioning individual leaves in stripping position, and stem gripping means comprising adjacent belts engaging and drawing each leaf stem as the leaves arrive at the stripping position.
14. In a tobacco stemming machine, co-operating stripping means including continuously moving elements, one of which moves lineally and comprises a flexible series of knives, and the other of which comprises a rotatively moving carding member, the latter member also acting to successively move individual leaves to stripping position, and stem gripping means comprising adjacent belts engaging and drawing each leaf stem as the leaves arrive at the stripping position.
15. In a tobacco stemming machine, stripping means, stem gripping means in combination therewith, and leaf straightening means acting to straighten the bunched stemmed leaves.
16. In a tobacco stemming machine, co-operating stripping means, one of which constitutes a leaf carrier, stem gripping means engaging and drawing each loose stem as the leaves arrive at the stripping position, and leaf straightening means acting upon the stemmed leaves.
17. In a tobacco stemming machine, co-operating stripping means, one of which comprises a rotating drum constituting a leaf carrier successively positioning individual leaves in stripping position, stem gripping means engaging and drawing each leaf stem as the leaves arrive at the stripping position, and leaf straightening means acting upon the stemmed leaves.
18. In a tobacco stemming machine, co-operating stripping means including continuously moving elements, one of which moves lineally and the other rotatively, for successively moving individual leaves to stripping position, stem gripping means engaging and drawing each leaf stem as the leaves arrive at stripping position, and leaf straightening means acting upon the stemmed leaves.

19. In a tobacco stemming machine, co-operating stripping means including continuously moving elements, one of which moves lineally and the other rotatively for successively moving individual leaves to stripping position, stem gripping means engaging and drawing each leaf stem as the leaves arrive at stripping position, and leaf straightening means acting upon the stemmed leaves.
- 5 20. In a tobacco stemming machine, co-operating stripping means, one of which comprises a flexible lineally moving member and the other a rotating drum constituting a leaf carrier successively positioning individual leaves in stripping position, stem gripping means engaging and drawing each leaf stem as the leaves arrive at the stripping position, and leaf straightening means acting upon the stemmed leaves.
- 10 21. In a tobacco stemming machine, co-operating stripping means, one of which comprises a lineally moving flexible member and the other a rotating drum constituting a leaf carrier successively positioning individual leaves in stripping position, stem gripping means engaging and drawing each leaf stem as the leaves arrive at the stripping position, and leaf straightening means acting upon the stemmed leaves.
- 15 22. In a tobacco stemming machine, co-operating stripping means, one of which comprises a lineally moving flexible knife member and the other a rotating drum constituting a leaf carrier successively positioning individual leaves in stripping position, stem gripping means engaging and drawing each leaf stem as the leaves arrive at the stripping position, and leaf straightening means acting upon the stemmed leaves.
- 20 23. In a tobacco stemming machine, co-operating stripping means including continuously moving elements, one of which moves lineally and the other of which comprises a rotatively moving carding member, the latter member also acting to successively move individual leaves to stripping position, stem gripping means engaging and drawing each leaf stem as the leaves arrive at stripping position, and leaf straightening means acting upon the stemmed leaves.
- 25 24. In a tobacco stemming machine, co-operating stripping means including continuously moving elements, one of which moves lineally and comprises a flexible series of knives, and the other of which comprises a rotatively moving brush member, the latter member also acting to successively move individual leaves to stripping position, stem gripping means engaging and drawing each leaf stem as the leaves arrive at stripping position, and leaf straightening means acting upon the stemmed leaves.
- 30 25. In a tobacco stemming machine, co-operating stripping means including continuously moving elements, one of which
- moves lineally and comprises a flexible series of knives, the other of which comprises a rotating drum having a peripheral brush area, the said drum constituting a leaf carrier for successively moving individual leaves to stripping position, stem gripping means engaging and drawing each leaf stem as the leaves arrive at stripping position, and leaf straightening means acting upon the stemmed leaves.
- 35 26. In a tobacco stemming machine, co-operating stripping means including continuously moving elements, one of which moves lineally while the other rotates, the latter also constituting a leaf carrier for successively moving individual leaves to stripping position, stem gripping means comprising adjacent belts engaging and drawing each leaf stem as the leaves arrive at the stripping position, and leaf straightening means acting upon the stemmed leaves.
- 40 27. In a tobacco stemming machine, co-operating stripping means, one of which comprises a lineally moving flexible member, and the other a rotating drum constituting a leaf carrier, successively positioning individual leaves in stripping position, stem gripping means comprising adjacent belts engaging and drawing each leaf stem as the leaves arrive at the stripping position, and leaf straightening means acting upon the stemmed leaves.
- 45 28. In a tobacco stemming machine, co-operating stripping means, one of which comprises a lineally moving flexible knife member, and the other a rotating drum constituting a leaf carrier successively positioning individual leaves in stripping position, stem gripping means comprising adjacent belts engaging and drawing each leaf stem as the leaves arrive at the stripping position, and leaf straightening means acting upon the stemmed leaves.
- 50 29. In a tobacco stemming machine, co-operating stripping means including continuously moving elements, one of which moves lineally and comprises a flexible series of knives, and the other of which comprises a rotatively moving carding member, the latter member also acting to successively move individual leaves to stripping position, stem gripping means comprising adjacent belts engaging and drawing each leaf stem as the leaves arrive at the stripping position, and leaf straightening means acting upon the stemmed leaves.
- 55 30. In a tobacco stemming machine, stripping means, stem gripping means in combination therewith, and leaf straightening means comprising mechanism releasably holding the butt end of the leaf and means engaging the apex end of the leaf and drawing it away from the butt end.
- 60 31. In a tobacco stemming machine, strip-

ping means, stem gripping means in combination therewith, and leaf straightening means comprising mechanism releasably holding the butt end of the leaf and including a pair of belts engaging the apex end of the leaf and drawing it away from the butt end.

32. In a tobacco stemming machine, stripping means, stem gripping means in combination therewith, and leaf straightening means comprising mechanism releasably holding the butt end of the leaf and including a pair of members engaging the apex end of the leaf and drawing it away from the butt end.

33. In a tobacco stemming machine, stripping means, stem gripping means in combination therewith, and leaf straightening means comprising mechanism releasably holding the butt end of the leaf and including a pair of contacting belts engaging the apex end of the leaf therebetween, said belts moving to draw the apex end of the leaf away from the butt end.

34. In a tobacco stemming machine, stripping means, stem gripping means in combination therewith, leaf straightening means comprising mechanism releasably holding the butt end of the leaf and including a pair of belts having engaging surfaces receiving the apex end of the leaf therebetween and drawing it away from the butt end, and means retarding movement of the butt end of the leaf.

35. In a tobacco stemming machine, stripping means, stem gripping means in combination therewith, leaf straightening means acting to straighten the bunched stemmed leaves, and leaf booking means.

36. In a tobacco stemming machine, co-operating stripping means, one of which constitutes a leaf carrier, stem gripping means engaging and drawing each loose stem as the leaves arrive at the stripping position, leaf straightening means acting upon the stemmed leaves, and leaf booking means.

37. In a tobacco stemming machine, co-operating stripping means, one of which comprises a rotating drum constituting a leaf carrier successively positioning individual leaves in stripping position, stem gripping means engaging and drawing each leaf stem as the leaves arrive at the stripping position, leaf straightening means acting upon the stemmed leaves, and leaf booking means.

38. In a tobacco stemming machine, co-operating stripping means including continuously moving elements, one of which moves lineally and the other rotatively, for successively moving individual leaves to stripping position, stem gripping means engaging and drawing each leaf stem as the leaves arrive at stripping position, leaf

straightening means acting upon the stemmed leaves, and leaf booking means.

39. In a tobacco stemming machine, co-operating stripping means including continuously moving elements, one of which moves lineally and the other rotatively for successively moving individual leaves to stripping position, stem gripping means engaging and drawing each leaf stem as the leaves arrive at stripping position, leaf straightening means acting upon the stemmed leaves, and leaf booking means.

40. In a tobacco stemming machine, co-operating stripping means, one of which comprises a flexible lineally moving member and the other a rotating drum constituting a leaf carrier successively positioning individual leaves in stripping position, stem gripping means engaging and drawing each leaf stem as the leaves arrive at the stripping position, leaf straightening means acting upon the stemmed leaves, and leaf booking means.

41. In a tobacco stemming machine, co-operating stripping means, one of which comprises a lineally moving flexible member and the other a rotating drum constituting a leaf carrier successively positioning individual leaves in stripping position, stem gripping means engaging and drawing each leaf stem as the leaves arrive at the stripping position, leaf straightening means acting upon the stemmed leaves, and leaf booking means.

42. In a tobacco stemming machine, co-operating stripping means, one of which comprises a lineally moving flexible knife member and the other a rotating drum constituting a leaf carrier successively positioning individual leaves in stripping position, stem gripping means engaging and drawing each leaf stem as the leaves arrive at the stripping position, leaf straightening means acting upon the stemmed leaves, and leaf booking means.

43. In a tobacco stemming machine, co-operating stripping means including continuously moving elements, one of which moves lineally and the other of which comprises a rotatively moving brush member, the latter member also acting to successively move individual leaves to stripping position, stem gripping means engaging and drawing each leaf stem as the leaves arrive at stripping position, leaf straightening means acting upon the stemmed leaves, and leaf booking means.

44. In a tobacco stemming machine, co-operating stripping means including continuously moving elements, one of which moves lineally and comprises a flexible series of knives, and the other of which comprises a rotatively moving brush member, the latter member also acting to successively move individual leaves to stripping position, stem

gripping means engaging and drawing each leaf stem as the leaves arrive at stripping position, leaf straightening means acting upon the stemmed leaves, and leaf booking means.

45. In a tobacco stemming machine, co-operating stripping means including continuously moving elements, one of which moves lineally and comprises a flexible series 10 of knives, the other of which comprises a rotating drum having a peripheral brush area, the said drum constituting a leaf carrier for successively moving individual leaves to stripping position, stem gripping 15 means engaging and drawing each leaf stem as the leaves arrive at stripping position, leaf straightening means acting upon the stemmed leaves, and leaf booking means.

46. In a tobacco stemming machine, co- 20 operating stripping means including continuously moving elements, one of which moves lineally while the other rotates, the latter also constituting a leaf carrier for successively moving individual leaves to 25 stripping position, stem gripping means comprising adjacent belts engaging and drawing each leaf stem as the leaves arrive at the stripping position, leaf straightening means acting upon the stemmed leaves, and leaf booking means.

47. In a tobacco stemming machine, co-operating stripping means, one of which comprises a lineally moving flexible member, and the other a rotating drum constituting 35 a leaf carrier, successively positioning individual leaves in stripping position, stem gripping means comprising adjacent belts engaging and drawing each leaf stem as the leaves arrive at the stripping position, 40 leaf straightening means acting upon the stemmed leaves, and leaf booking means.

48. In a tobacco stemming machine, co-operating stripping means, one of which comprises a lineally moving flexible knife 45 member, and the other a rotating drum constituting a leaf carrier successively positioning individual leaves in stripping position, stem gripping means comprising adjacent belts engaging and drawing each leaf stem 50 as the leaves arrive at the stripping position, leaf straightening means acting upon the stemmed leaves, and leaf booking means.

49. In a tobacco stemming machine, co-operating stripping means including continuously moving elements, one of which moves 55 lineally and comprises a flexible series of

knives, and the other of which comprises a rotatively moving brush member, the latter member also acting to successively move individual leaves to stripping position, stem 60 gripping means comprising adjacent belts engaging and drawing each leaf stem as the leaves arrive at the stripping position, leaf straightening means acting upon the stemmed leaves, and leaf booking means. 65

50. In a tobacco stemming machine, stripping means, stem gripping means in combination therewith, and leaf straightening means comprising mechanism releasably holding the butt end of the leaf and means 70 engaging the apex end of the leaf and drawing it away from the butt end, and leaf booking means.

51. In a tobacco stemming machine, stripping means, stem gripping means in combination therewith, leaf straightening means comprising mechanism releasably holding the butt end of the leaf and including a pair 75 of belts engaging the apex end of the leaf and drawing it away from the butt end, and 80 leaf booking means.

52. In a tobacco stemming machine, stripping means, stem gripping means in combination therewith, leaf straightening means comprising mechanism releasably holding 85 the butt end of the leaf and including a pair of members engaging the apex end of the leaf and drawing it away from the butt end, and leaf booking means.

53. In a tobacco stemming machine, stripping means, stem gripping means in combination therewith, and leaf straightening means comprising mechanism releasably holding the butt end of the leaf and including 90 a pair of contacting belts engaging the apex end of the leaf therebetween, said belts moving to draw the apex end of the leaf 95 away from the butt end, and leaf booking means.

54. In a tobacco stemming machine, stripping means, stem gripping means in combination therewith, leaf straightening means comprising mechanism releasably holding the butt end of the leaf and including a pair 100 of belts having engaging surfaces receiving the apex end of the leaf therebetween and drawing it away from the butt end, means 105 retarding movement of the butt end of the leaf, and leaf booking means.

In testimony whereof I have hereunto affixed my signature.

JOHN O. MORRIS.
